UNITED STATES PATENT OFFICE.

GEORGE McD. JOHNS, OF ST. LOUIS, MISSOURI, ASSIGNOR, BY MESNE ASSIGNMENTS, TO THE INDUSTRIAL PROCESS ENGINEERING COMPANY, A CORPORATION OF DELAWARE.

TOP OR ROOF FOR FURNACES OR RETORTS.

Application filed December 6, 1920. Serial No. 428,593.

To all whom it may concern:

Be it known that I, GEORGE McD. JOHNS, a citizen of the United States, residing at the city of St. Louis, State of Missouri, have invented a certain new and useful Improvement in Tops or Roofs for Furnaces or Retorts, of which the following is a specification, reference being had to the accompanying drawings, forming a part hereof.

This invention relates generally to reduction furnaces, retorts, and the like and, more particularly, to a certain new and useful improvement in tops or roofs for furnaces or retorts especially designed for the extraction by distillation or vaporization of oil from shale and other oil-bearing materials.

An object of my present invention is to provide a furnace or retort roof or top so constructed as to facilitate the flow of the vapor to the condensers, and to such end and more specifically to provide a furnace top or roof which includes a vapor-conduit, take-off boxes, and roof-members, the box and roof-members being so shaped and co-operating as to conduct or direct the vapor from the retort body into the conduit for later condensation purposes.

Another object of my present invention is to provide a furnace or retort top or roof made up of or which includes a plurality of co-operating separable sections, whereby the roof is elastic, as it might be described, for adaptability to different size furnaces and also easily removable or replaceable, either as an entirety or in parts, for purposes of repair or for permitting convenient access to the furnace-interior.

An additional object of my present invention is to provide a sectional furnace or retort roof or top, the several sections of which may be easily fabricated and readily assembled in covering or roofing position upon the retort-body or setting.

With the above and other objects in view, my present invention resides in the novel features of form, construction, arrangement, and combination of parts hereinafter described and afterwards pointed out in the claims.

In the accompanying drawings,

Figure 1 is a side elevational view of a furnace-top or roof embodying my invention, a portion of the conduit being broken away;

Figure 2 is a plan view of the furnace-top or roof;

Figure 3 is a transverse sectional view of the roof or top, showing a portion of the furnace-setting, taken through one of the take-off boxes on approximately the line 3—3, Figure 2;

Figure 4 is a similar view, taken, however, through one of the top or roof-plates on approximately the line 4—4, Figure 2;

Figure 5 is a longitudinal sectional view of the furnace-top or roof taken approximately on the line 5—5, Figure 2.

Referring now more in detail to the said drawings, which illustrate a practical embodiment of my invention and in which like reference characters refer to like parts throughout the several views, 1 designates the furnace-setting, which may be of any standard or approved form and construction common to furnaces of the reduction or distillation type in which relatively high temperatures are created and maintained, such setting generally comprising a brick exterior and a lining of suitable refractory material and being usually of rectangular oblong configuration.

Suitably mounted, and preferably removably fastened or held in place, upon the setting 1, is a retaining-frame for the several roof sections or members. This frame is composed preferably of angle-members 2 connected at their ends by angle-plates 3 and rivets or the like 4, the horizontal flanges of the frame-members 2 resting upon the setting 1 and the other or vertical flanges of the frame-members 2 being presented upwardly with their outer face substantially flush with, or in the plane of, the outer face of the setting.

At approximately the longitudinal center of the furnace setting 1 here illustrated, and spanning the setting with their ends resting upon the horizontal flanges of the frame side-members 2, is a pair of beams 5 preferably of angle-iron of L-section; and fixed between the vertical flanges of the beams 5 and depending from the beams into the setting for some little distance below or beneath the plane of the frame 2, for purposes later appearing, is a so-called baffle-plate 6.

Disposed intermediate the beams 5 and

the end frame-members 2, is a plurality of suitably spaced so-called beams 7—7, which are also preferably of angle-iron of L-section and, like the beams 5, span the open setting with their ends resting upon the horizontal flanges of the opposite frame side-members 2. Each of the beams 7 is bent, as best seen in Figures 3 and 4, and thereby divided and shaped to incline downwardly and outwardly from approximately its longitudinal center, the apex of the beam being disposed approximately in, or adjacent to, the transverse center of the furnace and rising above the beam-ends resting upon the frame side-members 2. These beams 7 are suitably spaced in pairs with their horizontal flanges presented outwardly or towards the opposite ends of the furnace-setting, as best seen in Figures 1 and 2, and provide or constitute what might be designated the laterals or supports for the several roof sections.

8—8 are sections, preferably metal plates, which constitute or provide the side-members or walls of so-called vapor take-off boxes for the furnace. These sections 8, which are also arranged in pairs, are shaped or formed at their lower edges or margins to conform with the bent beams or laterals 7 and at their said lower margins or edges are fixed, as by rivets 9, to and upon the inner-faces of the vertical legs or flanges of the beams 7, as best seen in Figures 2 and 3. The walls or sections 8 at their upper margins or edges, however, are shaped to continuously incline from end to end of the box or from one to the other side of the furnace; as here shown, reference being particularly had to Figures 3 and 4, the wall sections 8 at their upper margins or edges slope upwardly from the left to the right hand side of the furnace setting 1, the box being consequently larger in area at its outlet or right-hand end than at its opposite or left-hand end. Riveted or otherwise fixed to and upon the inner-face of walls 8 at their sloping upper margins or edges, are suitable angles 10, to which angles 10 are fixed, as by rivets 11, suitable preferably metallic and correspondingly sloping sections 12, which connect the walls 8 at their upper margins and constitute or provide the tops or upper walls of the take-off boxes.

As best seen in Figures 3 and 4, the take-off boxes, so formed of the connected sections or walls 8 and 12, have a length, that is to say, a dimension transversely of the furnace, which falls somewhat short of the length of the beams or laterals 7; and extending longitudinally of the furnace, with one side wall fixed or riveted, as by upright angle-members 13, to the right-hand or outlet margins or edges of the take-off box walls 8—8, is a continuous conduit 14 adapted for communication with the several take-off

boxes of the top, the conduit 14 being provided at each take-off box with a suitable communicating opening 15, and the inner-wall of the conduit at each opening 15 being suitably provided with a sliding door or shutter 16 for closing or cutting off communication with the particular box. As shown in Figure 3, the upper wall of the conduit adjacent each door 16 is suitably provided with a so-called man-hole 17, removably closed by a plate 18, for permitting convenient access into the conduit for closing or opening the shutters or doors 16.

Completing the present roof and disposed at the opposite sides of each of the take-off boxes, are suitable preferably metallic sections or plates 19—20. Each of the plates 19—20, and it will be understood that each of these plates may be formed integrally in one piece or of co-operating separable sections, are so shaped at their inner margins or edges to conform with the bent shape of the beams or laterals 7, a plate 19 being disposed upon one side of a take-off box with its opposite straight ends resting upon the horizontal flanges of the opposite frame side-members 2, its outer straight side margin resting loosely or removably upon the horizontal flange of the adjacent frame end-member 2, and its inner bent side or margin resting upon the adjacent beam or lateral 7, and a plate 20 being disposed upon the opposite side of said take-off box and similarly having its opposite straight ends resting upon the horizontal flanges of the opposite frame side-members 2, its one straight side or margin resting upon the adjacent cross-beam or support 5, and its other or bent side or margin resting upon the bent beam or lateral 7 at the adjacent side of the box. The plates 19—20, being shaped as described, incline in both directions upwardly and laterally and provide what may be described as an inverted hopper leading into the take-off boxes.

For sealing the various joints or seams in the top of the roof so sectionally constructed, I may, if required, although not here shown, resort to the common expedient of filling sand or its equivalent over the various plates and between the confines of the vertical flanges of the retaining frame composed of the angle-members 2.

From the foregoing description, it will be evident that, in use, the various sections of the roof may not only be readily manufactured or fabricated, but also easily assembled in roofing position upon the furnace-setting, and that, further, any one or all of the sections may with facility be removed for replacement or to provide convenient access to the furnace interior for repairs or adjustments. The roof also facilitates the flow of the vapor from the retort-body to the condensers, the several roof plates being

the size of the particular furnace setting. The double plates of said cross-arms 5 will of course correspondingly vary with the size required in order to stanch all losses. The several flue-plates 6 dividing the interior of the furnace into several compartments for directing the vapor from the body of the furnace or reservoir into one or the other of the flues of flues.

I am aware that changes in the form, size, construction, arrangement, and combination of the several parts of this furnace may be made and substituted for those herein shown, which do not detract from the fundamental principle of my invention.

Having thus described my invention, what I claim and desire to secure by Letters Patent is:

1. A refractory including a furnace chamber having a larger base at one end than at the other and comprising spaced side walls sloping from end to end at their upper margins and a connecting top wall disposed upon the sloping margins of the side walls, the upper margins of the side walls meeting the lower margins of the side walls at the smaller end of the furnace.

2. A refractory including a furnace chamber comprising spaced side walls, lower margins oppositely inclined downwardly and outwardly from approximately their longitudinal center, and a top wall disposed upon the upper margins of the side walls, inclining with vapor conducting plates having clear side margins corresponding to shaped slots or drains with the above margins of the opposite side walls of the furnace.

3. A refractory including a furnace chamber comprising spaced side walls, lower margins oppositely inclined downwardly and outwardly from approximately their longitudinal center, a top wall disposed upon the upper margins of the side walls, and plates disposed upon the opposite side of the side walls, the plates being disposed upon the opposite side of the side walls of the furnace, the plates having clear side margins corresponding to slots or drains with the above margins of the side walls of the furnace.

4. A furnace chamber having a

bottom, a top, and a vertical vapor conducting loop disposed at opposite sides of the bottom into the top.

5. A refractory including a furnace chamber comprising a pair of spaced side walls sloping upper margins sloping upwardly from one end of the furnace to the other and enclosed above, the margins oppositely sloping downwardly said outwardly from approximately the longitudinal center of the furnace, and a sloping upper wall fixed upon the sloping upper margins of the side walls, vapor conducting loops comprising plates disposed at the opposite sides of the furnace and inclining in both directions toward the longitudinal center of the furnace, and a conduit disposed at an angle of the furnace and a loop fixed to the longitudinal center of the furnace.

6. A refractory including a furnace chamber comprising a pair of spaced side walls enclosing upper margins sloping upwardly from

one end of the furnace to the other and whose lower margins oppositely sloping downwardly and outwardly from approximately the longitudinal center of the furnace, and a sloping upper wall fixed upon the sloping upper margins of the side walls, vapor conducting loops comprising plates disposed at the opposite sides of the furnace and inclining in both directions toward the longitudinal center of the furnace, and a conduit disposed at an angle of the furnace and a loop fixed to the longitudinal center of the furnace.

7. A refractory including a furnace chamber comprising a pair of spaced side walls enclosing upper margins sloping upwardly from the longitudinal center of the furnace to the other end whose lower margins oppositely sloping downwardly and outwardly from approximately the longitudinal center of the furnace, and a sloping upper wall fixed upon the sloping upper margins of the side walls, vapor conducting loops comprising plates disposed at the opposite sides of the furnace and inclining in both directions toward the longitudinal center of the furnace, and a conduit disposed at an angle of the furnace and a loop fixed to the longitudinal center of the furnace.

8. A refractory including a furnace chamber comprising a pair of spaced side walls enclosing upper margins sloping upwardly from the longitudinal center of the furnace to the other end whose lower margins oppositely sloping downwardly and outwardly from approximately the longitudinal center of the furnace, and a sloping upper wall fixed upon the sloping upper margins of the side walls, vapor conducting loops comprising plates disposed at the opposite sides of the furnace and inclining in both directions toward the longitudinal center of the furnace, and a conduit disposed at an angle of the furnace and a loop fixed to the longitudinal center of the furnace.

9. A refractory including a pair of spaced

beams shaped to incline downwardly and outwardly from approximately their longitudinal center, in combination with a vapor take-off box having support at the lower 5 margins of its side walls upon the beams, the side walls of the box being shaped to conform at their lower margins with the shape of the beams, and vapor-conducting plate-sections disposed upon opposite sides 10 of the box and supported at a margin by the beams, the plates being also shaped at their said margins to conform with the shape of the beams.

10. A retort-top including a frame, a pair 15 of spaced beams supported at their ends by the frame, a take-off box having support at its side walls upon the beams, a plurality of plates disposed upon opposite sides of the box and supported at their margins by the 20 beams and the frame, and a conduit supported over the beams and plates and adapted for communication with the take-off box.

11. A retort top including a frame of 25 angle-iron construction adapted for location upon the furnace-setting, a pair of spaced angle-iron laterals supported at their ends by the frame, a take-off box having support at its side walls upon the laterals and rising above the frame, a plurality of roof- 30 plates supported by the frame and laterals, and a conduit having engagement with the take-off box and disposed over an end of the plates and beams, the conduit being adapted for communication with the take-off box.

12. A retort top including a frame of 35 angle-iron construction adapted for location upon the furnace-setting, a pair of spaced angle-iron laterals supported at their ends by the frame, a take-off box having support at its side walls upon the laterals and rising above the frame, a cross-beam supported at its ends by the frame, a plurality 40

of plates supported by the frame, laterals, and beam, and a conduit having engagement with the take-off box and disposed over an end of the plates and beams, the conduit being adapted for communication with the take-off box. 45

13. A furnace roof including a plurality 50 of vapor take-off boxes each comprising spaced side walls and a top wall and each having a larger dimension at one end than at the other, and a conduit disposed at an angle to, and adapted for communication with the 55 larger end of, each of said boxes.

14. A retort roof including a plurality of 60 vapor take-off boxes each comprising spaced side walls and a top wall and each having a larger dimension at one end than at the other, a vapor conducting conduit disposed at an angle to and adapted for communication with each of said boxes, and means for controlling communication between the conduit and the several respective boxes. 65

15. A retort roof including a pair of 70 spaced vapor take-off boxes each comprising a pair of spaced side walls and a top wall, a pair of oppositely disposed inverted hopper-shaped roof plates disposed between 75 and leading into the pairs of respective boxes, and a baffle-plate disposed between the hopper-plates.

16. A retort top or roof including a pair 80 of spaced take-off boxes, a pair of cross-beams disposed intermediate the boxes, a pair of oppositely disposed hopper-shaped plates leading into the respective boxes and disposed respectively between the cross-beams and the boxes, and a baffle-plate fixed 85 to the cross-beams and disposed between the hopper-plates. 90

In witness whereof, I have signed my name to this specification.

GEORGE McD. JOHNS.
